UNITED STATES PATENT OFFICE.

ROBERT EMANUEL KRISTENSSON, OF LIDINGO, SWEDEN.

VERTICAL CARD SYSTEM.

Application filed March 30, 1927, Serial No. 179,653, and in Sweden February 15, 1927.

This invention relates to card systems of the type in which the cards are stored in vertical position in a cabinet, compartment or casing of any desired or suitable construction.

In card systems of said type the cards generally rest with their lower edge on the bottom of the cabinet or casing. Systems of this kind are known in which means are provided which allow the raising of each single card and its turning over horizontally toward the front or the rear of the casing for making the desired entry thereon, means being further provided which normally retain the raised card and prevent it from being removed from the cabinet or casing.

The chief object of this invention is to improve and simplify such card systems so as to facilitate the entry of record matter on the cards when fully raised up from their normal position and turned over in the one or other direction.

Another object of the invention is to provide simple means for the retaining of the raised cards in the receptacle or casing and for allowing their insertion and removal from the casing when desired.

A further object of the invention is to strengthen the cards by carrying out the supporting and retaining means of the cards as strengthening reinforcements on the upper and lower edges of the cards.

With these and other objects in view the invention consists, chiefly, in the provision at the longitudinal sides of the receptacle or casing of guiding bars adapted to support the cards in hanging position, projections being further provided at the upper corners of the cards by means of which they are suspended on said guide bars without abutting against the bottom of the receptacle. By this suspension arrangement the cards always take up a vertical position in the receptacle so that their upper edges together form a table-like flat surface which can steadily support a raised card when an entry is to be made thereon.

The said guide bars are preferably also utilized as retaining means for the cards by the cards being provided also at their lower corners with projections forming abutments which in raising the card strike against the guide bars so that the card is prevented from being removed.

The said projections or extensions can be

formed either directly from the card board or by providing at the upper and lower edges of the cards metallic reinforcements extending beyond the vertical edges of the cards, or the extensions may be provided on card holders adapted to receive the usual rectangular cards.

In the accompanying drawings, I have shown one embodiment of my invention. Fig. 1 is a perspective view of a card casing according to this invention. Fig. 2 is a plan thereof on a larger scale. Fig. 3 is a vertical section on the line III—III of Fig. 2. Fig. 4 is a plan of a portion of one supporting bar and means for operating same and Fig. 5 is a sectional view thereof; Fig. 6 is an end view of a guide card.

Referring now to the drawing, 1 represents a receptacle or casing adapted to receive a large number of file cards 2 placed behind guide cards 3, the latter having any desired indication. The upper edge of each card is provided with a metallic reinforcement 4 forming at both ends projections 5, 6 by means of which the card is suspended on supporting bars 7 and 8 respectively secured to the longitudinal side walls of the receptacle 1. The lower edge of each card is likewise provided with a metallic reinforcement 9 forming at both ends projections 10 and 11 which on raising a card from its normal position for making an entry thereon strike against the bars 7 and 8 respectively and stop the card in such position that a hinge crease 12 thereon is level with the upper edges of the cards resting in normal positions in the receptacle. The raised card can then be bent over in one or the other direction until it rests on the flat surface formed by the upper edges of the cards resting in suspended position in the receptacle as is illustrated in Fig. 1. The upper projections of the guide cards are, preferably, at one or both sides provided with horizontal tabs 13 adapted to receive the indicia according to which the cards stored in the receptacle are classified. In the embodiment shown the supporting bar 8 is movable laterally to such extent that the projection 11 of a card can pass by it when the card is to be inserted or removed, the insertion and removal taking place in such manner that the card is turned to a somewhat oblique position, inasmuch as the lateral movement of the guide bar 8 ought not

to be so great that the cards stored in the casing

lose their support. The means for effecting the lateral movement of the bar 8 consists in the embodiment shown of an eccentric 14 journalled on a short vertical shaft 16 in the wall of the receptacle and engaging an oblong hole 15 in the bar and being rotatable by means of a key adapted to engage a groove 17 formed in the top of the eccentric or in any other suitable manner.

10. What I claim is:

1. A vertical card system, comprising a receptacle having parallel supporting bars at two of its side walls, and cards having projections at their upper corners adapted to hold the cards suspended in vertical positions on said supporting bars, and projections at the lower corners adapted to strike against the supporting bars in raising the card from its normal position in the receptacle, thus preventing the card from being removed from the receptacle.

2. A vertical card system, comprising a receptacle having parallel supporting bars at two of its side walls, cards having reinforcements at their upper and lower edges, projections from said upper reinforcements extending beyond the vertical edges of the cards and adapted to support the cards in hanging position on said supporting bars, and projections from said lower reinforcements adapted to strike against the supporting bars when raising the card from its normal position in the receptacle, thus prevent-

ing the card from being removed from the receptacle.

3. A vertical card system, comprising a receptacle having parallel supporting bars at two of its side walls, means for laterally moving one of said supporting bars, and cards having means to suspend them in hanging position on said supporting bars and means adapted to strike against the supporting bars when raising the card from its normal position in the receptacle.

4. A vertical card system, comprising a receptacle having parallel supporting bars at two of its side walls, file cards and guiding cards having projections at their upper corners adapted to rest on said supporting bars so as to hold the cards in hanging position in the receptacle, the projections of the guide cards having tabs adapted to receive indications.

5. A card for vertical card systems, having projections at the upper and lower corners extending beyond the vertical sides of the card, the upper projections being of greater length than the lower projections.

6. A card for vertical card systems, having reinforcements at its upper and lower edges, said reinforcements extending beyond the vertical sides of the card so as to form projections at the corners of the card.

In testimony whereof I have signed my name.

ROBERT EMANUEL KRISTENSSON.
